UNITED STATES PATENT OFFICE.

ISAAC BANK, OF HAMMONTON, NEW JERSEY.

SLEEVE-FORMER.

1,345,739.

Specification of Letters Patent.

Patented July 6, 1920.

Application filed August 5, 1919. Serial No. 315,392.

To all whom it may concern:

Be it known that I, ISAAC BANK, a citizen of the United States, residing in the city of Hammonton, county of Atlantic, and State of New Jersey, have invented a new and useful Sleeve-Former, of which the following is a specification.

My invention relates to the class of devices which are used by garment-makers for the ironing of the sleeves of garments, and its primary object is the construction of an extensible sleeve-former which will hold a garment sleeve fully stretched and rounded along its inner and outer longitudinal edges, so as to permit of the ironing along such edges in rounded and not flat form.

Broadly considered, my invention comprehends an extensible and compressible sleeve former, composed of two properly curved forming blocks, which together embody the general proportions and outline of a garment sleeve, and which are adapted to be brought together by manual compression and retained by the sleeve when upon them, and then to be mechanically extended by the extending devices which my former embodies and my invention embraces.

For the purpose of illustrating my invention, I have shown in the accompanying drawings a certain type and embodiment of it which is at present preferred by me because in practice it has given satisfactory and reliable results.

It is to be understood, however, that the various components in which my invention is shown as embodied, can be variously arranged and proportioned, and that my invention is not, therefore, limited to the precise arrangement and organization which is typified in the sleeve former represented in the accompanying drawings and herein described.

Referring to the drawings:

Figure 1 represents a plan view of a typical sleeve former embodying my invention.

Fig. 2 represents my sleeve former in its extended position, in transverse section on the line 2-2 of Fig. 1, with a sleeve in place upon it and the forming blocks and separating means compressed to stretch the sleeve.

Fig. 3 is a view similar to Fig. 2, but showing the position of the parts when the

sleeve has not been put in place, and the forming blocks are separated.

Fig. 4 is a fragmentary, plan view upon an enlarged scale, of the upper portion of the sleeve former.

Fig. 5 is a perspective view of the spring-
inclosing sleeve removed from the forming blocks; and

Fig. 6 is a perspective view of the stop rod similarly removed from the forming blocks.

Similar numerals of reference indicate corresponding parts.

Referring to the drawings:

1 and 2 represent the two properly curved forming blocks, which together constitute the elemental members and my sleeve former.

Each of these blocks is preferably made of wood, flat upon both sides, and curved so that, when in their related position, they correspond to the general outline of the sleeve of a garment when laid flat for ironing.

As illustrated particularly in Figs. 2 and 3, the outer edges of the two forming blocks are rounded or curved, so that when the sleeve has been put in place upon them, its outer and inner edges, as already mentioned, will be stretched round instead of being left flat.

The outline and curvature of the two forming blocks is such as practice may indicate as desirable, the upper ends being curved and the lower ends preferably straight, as shown in Fig. 1.

Assume that in the normal mounting of the parts it is desired to have the two inner or facing edges 5 and 6 of the blocks 1 and 2 maintained at such distance apart as it is desired that the two blocks shall occupy when the sleeve has been drawn over them to be stretched—I provide means which I term separating means, adapted normally or when the former is not in use, to hold its blocks apart at a desired distance as shown in Figs. 1, 3 and 4, and both to permit of the degree of the compression necessary to bring together the two blocks for the drawing over them of the sleeve, and also to occasion their extension or separation to the degree necessary to stretch the sleeve to the extent desired, and further, when the sleeve is not upon the blocks, to prevent the blocks themselves from falling apart.

The means so provided for effecting this

compression and separation of the blocks is the following:—

Within both of the blocks, and near their respective upper and lower ends and entering their inner edges, I form block sockets 7, being channels in approximately right angular position relatively to the lengths of the blocks.

Entered within both sockets 7, and there 10 are preferably two pairs of sockets, of which I will describe only one pair,—is a spiral spring 8, the ends of which abut against transverse stop pins 9 driven through the sides of the forming blocks, and through the 15 block sockets, preferably near the middle of each socket.

These pins 9 are fastened permanently, and are driven through a cylindric stop rod 10, longitudinally slotted at 11 throughout 20 its length, so that in the assemblage of the parts, the rod will be stayed by the contact of the pins with the closed ends 12 of its slot.

13 designates a spring-inclosing hollow, 25 cylindric sleeve, adapted to be fixedly secured at one end, 14, to one of the block sockets 7 of one of the forming blocks, and at the other end, 15, free to move endwise within the opposite socket 7. As to a certain 30 part of its length this sleeve is slotted longitudinally and diametrically as at 16, so as to permit of the passage and movement through it of one of the stop pins 9.

The result of this arrangement, as will be 35 obvious, is to permit of the controlled separation of the two forming blocks to stretch a garment sleeve upon them, by the expanding action of the coil spring,—the limitation of the expansion action being due to 40 the contact of the pins 9 with the closed ends 12 of the stop rod 10,—and also to permit of the controlled compression of said forming blocks for the slipping on them of the garment sleeve.

45 Thus it will be observed that in Fig. 3, in which the spring 8 is shown as extended, the closed ends 12 of the stop rod 10 are in contact with the pins 9, whereas, in the position of the parts shown in Fig. 2, the 50 spring is under compression by reason of the sleeve former as a whole having been entered within the fabric of the sleeve, designated as 17.

In the mounting of the parts, the functioning 55 of the slotted spring-inclosing sleeve 13, is not only to inclose the spring 8, but also, in conjunction with the slotted stop rod 10 and the stop pins 9, to assure the connection of the forming blocks, which in the 60 practical use of the device as an entirety are vital elements.

As already explained, the dimensions and proportions of the several elements which together compose my sleeve former, may be

modified, so long as their functional attributes are not departed from.

Having thus described my invention, what I claim as new and desire to secure by Letters Patent, is:—

1. A sleeve former which comprises in combination the following elements:—a pair of oppositely-disposed forming blocks which when placed together possess a longitudinally curved external shape and are formed with opposite sockets,—means for connecting said forming blocks which embrace a hollow, cylindrical, slotted rod the ends of which enter sockets in the forming blocks,—stop pins which pass through the sockets in the forming blocks, are fixedly 80 connected to said blocks and pass through the slot in the stop rod,—and a spring encircling the stop rod and bearing at its ends against the stop pins,—whereby the forming blocks can be compressed together 85 by compressing the spring and be separated by the expansion of the spring.

2. A sleeve former which comprises in combination the following elements:—a pair of oppositely-disposed forming blocks 90 which when placed together possess a longitudinally curved external shape and are formed with opposite sockets,—means for connecting said forming blocks, which embrace a hollow, cylindrical, slotted stop rod 95 the ends of which enter sockets in the forming blocks,—stop pins which pass through the sockets in the forming blocks, are fixedly connected to said blocks, and pass through the slot in the stop rod,—a spring 100 encircling the stop rod and bearing at its ends against the stop pins,—and a hollow spring-inclosing sleeve, one end of which is of one of the forming blocks and the other end of which is slotted and slidably entered 105 within a notch in the opposite forming block, a stop pin of which block passes through it.

3. A sleeve former comprising:—a pair of oppositely corresponding flat forming 110 blocks, the inner and facing edges of which are formed with opposite sockets,—a hollow, cylindrical, longitudinally slotted stop rod, introduced between the forming blocks, the ends of which are entered within the sockets 115 in said blocks,—stop pins passing through the sockets of the forming blocks and through the slot in the stop rod,—and a spiral spring encircling the stop rod and interposed between the stop pins and within 120 the sockets of the blocks.

4. A sleeve former comprising:—a pair of oppositely corresponding flat forming blocks, the inner and facing edges of which are formed with opposite sockets,—a hollow, cylindrical, longitudinally slotted stop rod introduced between the forming blocks, 125 the ends of which are entered within the

sockets in said blocks,—stop pins passing through the sockets of the forming blocks and through the slot in the stop rod,—a spiral spring encircling the stop rod and interposed between the stop pins and with 5 in the sockets of the blocks,—and a hollow spring-inclosing slotted sleeve one end of which is fastened to one of the forming

blocks, and the other end of which is free to move within the opposite socket of the opposite block.
